CLAIM

The ornamental design for a holder for game chips, as shown and described.

DESCRIPTION

FIG. 1 is a perspective view of a holder for game chips showing my new design;

FIG. 2 is a right side elevation thereof, the left side elevation being a mirror image thereof;

FIG. 3 is a top plan view thereof;

FIG. 4 is a bottom plan view thereof;

FIG. 5 is a front elevation thereof; and

FIG. 6 is a rear elevation thereof.

FIG.1

FIG.2

FIG.4

FIG.3
